UNITED STATES PATENT OFFICE

142,501

DESIGN FOR A MULTIPLE PICTURE FRAME

Isaac B. Sherr, Los Angeles, Calif.

Application March 7, 1945, Serial No. 118,295

Term of patent 7 years

(Cl. D29—20)

To all whom it may concern:

Be it known that I, Isaac B. Sherr, a citizen of the United States and a resident of Los Angeles, county of Los Angeles, State of California, have invented a new, original, and ornamental Design for a Multiple Picture Frame, of which the following is a specification, reference being had to the accompanying drawing, forming part thereof.

I claim:

The ornamental design for a multiple picture frame, substantially as shown.

ISAAC B. SHERR.
